UNITED STATES PATENT OFFICE.

THOMAS WOODS, OF NICHOLASVILLE, KENTUCKY.

IMPROVEMENT IN STONE-DRILLS.

Specification forming part of Letters Patent No. 179,636, dated July 4, 1876; application filed January 22, 1875.

To all whom it may concern:

Be it known that I, THOMAS Woods, of Nicholasville, Jessamine county, State of Kentucky, have invented a certain new and useful Improvement in Tripping and Elevating Devices for Rock-Drills, Trip-Hammers, &c., of which the following is a specification:

My invention is designed as an improvement upon the device for which Letters Patent of the United States were granted to me December 4, 1866; and consists, in the first part, in forming the tripping-pulley of same with a sloping edge of gradually-increasing curvature, for the purpose of lessening the amount of wear upon the chain or rope, and at the same time lose the least amount of power in slippage. My invention consists, in the second part, in the provision of a swiveling block in the drill-chain, between the drill-head and tripping-pulley, to guard against torsion, and provide for the free play of the drill; and my invention consists, in the third part, in the provision of an idler-pulley in line with the tripping-pulley and a drum attached to the horse-power, by the use of which mechanism the drill rope or chain can be drawn in or wound up conveniently.

Figure 1 of the accompanying drawings is a perspective view of a stone-drill embodying my invention. Fig. 2 is a front elevation of the tripping-pulley. Fig. 3 is a side elevation of the same. Fig. 4 is a detached view of the swiveling block.

A is the driving-wheel of the horse-power, to which is secured the draft-beam *a*, and a drum, *a'*. It is fitted with bevel gear-teeth, to engage with and operate the bevel-pinion B, attached to the shaft *b*, to which the tripping-pulley C is secured. The shaft *b* is secured in bearings on a bed-plate, D, which also supports the horse-power A *a* *a'*. Rising from this bed-plate D, just in front of pulley C, is a derrick-post, E, somewhat taller than the drill-shank, and fitted with an idler-pulley, *e*, for the drill-chain F and rope to travel on.

The chain F, as seen in Fig. 1, passes over pulley *e*, and, as seen in Figs. 1, 2, and 3, attaches itself to the pulley C as follows: The pulley C has a grooved periphery, *c*, with the flange G preserved entire, while the flange H is cut away in the form of a cam, commencing at the desired point H' on the periphery, and running inwardly to bottom of groove *c* at H'', with its outer edge cut away

in the form of a curved slope, H''', with gradually-increasing breadth of curved surface to same point H'', where both sloping edge and cam-surface abruptly give way to the natural surface of flange H.

To a point at the commencement of the surface H, or any other within its limit, is secured, in groove *c*, the end of chain F.

When the machine is set in motion, the pulley C, revolving in the direction of the arrow, as seen in Fig. 2, winds the chain into the groove *c*, and accordingly raises the drill to a height equal almost to the periphery of groove *c*, or until the first contact of chain F from the drill is at H'', where there is no support for it, on account of the shape of the cam H' H''', when the weight of the drill starts the chain from the groove, and the said cam H' H''' completely removes it, leaving the drill to make its blow unretarded; and it is evident that the shape of cam H' H''', being curved as it is, provides for the least amount of wear upon the chain, and least amount of lost power in slippage.

It is also obvious that the chain, in being carried around pulley C, will acquire a certain amount of twist, which I propose to remedy by means of swiveling block *f*.

When the drill has been sunk to considerable depth, and it is desired to withdraw it, it is only necessary to pass the lifting-rope (shown in dotted lines in Fig. 1) over pulley *e*, pulley I, and attach it to drum *a'*, around which it can be wound, and the drill be pulled out by the same horse-power.

I claim—

1. For a stone-drill or analogous use, the revolving converse-sloping cam and grooved pulley C *c* *G* *H* *H'* *H''* *H'''*, constructed, connected, and operating substantially as and for the purpose specified.

2. In combination with pulley C, constructed as described, and pulley *e*, and chain F of a stone-drill, the swiveling socket-link *f*, substantially as and for the purpose specified.

3. In combination with pulley *e* and drum *a'* on horse-power, the idler-pulley I, connected and operating substantially in the manner and for the purpose specified.

In testimony of which invention I hereunto set my hand.

THOMAS WOODS.
